CLAIM

The ornamental design for a jewelry display case, as shown and described.

DESCRIPTION

FIG. 1 is a perspective view of a first embodiment of a jewelry display case with the door in an open position showing our new design;

FIG. 2 is a front elevational view thereof with the door in a closed position;

FIG. 3 is a top elevational view thereof;

FIG. 4 is a side elevational view thereof, the opposite side being a mirror image thereof;

FIG. 5 is a bottom plan view thereof; and,

FIG. 6 is a rear elevational view thereof.

FIG. 1.

FIG. 2.

FIG. 3.

FIG. 4.

FIG. 5.

FIG. 6.
